UNITED STATES PATENT OFFICE.

EDWARD A. CUNNIF, OF WALTHAM, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

Application filed September 23, 1924. Serial No. 739,328.

To all whom it may concern:

Be it known that I, EDWARD A. CUNNIF, a citizen of the United States, residing at Waltham, county of Middlesex, and State 5 of Massachusetts, have invented an Improvement in Feeler Mechanisms for Looms, of which the following description, in connection with the accompanying drawings, is a specification, like characters on the 10 drawings representing like parts.

This invention relates to feeler mechanisms for looms and more particularly to the intermittent type of such mechanisms wherein the detecting element is held in an 15 inoperative position during periods of inactivity and is released at intervals to perform its feeling function.

In the use of a feeler mechanism wherein there is a penetrating member adapted to 20 penetrate the filling and be given its feeling and exhaustion-indicating movement when the filling reaches a critical period, the recurring contact of the penetrating feeler is liable to cause injury to the filling. 25 This is especially observable in some kinds or characters of filling, such as, for instance, silk or filling of fine count.

One of the objects of the present invention is to provide a feeler mechanism of the 30 penetrating type wherein the penetrating member is movable to a position beyond the reach of the filling on detecting beats during its periods of inactivity, with the result that all injury liable to occur by reason of 35 the penetrating member contacting with the filling is obviated.

In accordance with the present invention, the feeler mechanism comprises an impinging feeler and a penetrating feeler, both of 40 which are held in a frontward inoperative position beyond the reach of the filling during periods of inactivity and are released at intervals during weaving with the same supply of filling in the shuttle.

45 A further novel feature of the invention consists in means for moving both the penetrating and impinging feelers to a frontward position beyond the reach of the filling on detecting beats.

50 The invention, new combination of parts, and novel features thereof, will best be made clear from the following description and the accompanying drawings of one good form thereof.

55 In the drawings:

Fig. 1 is a perspective view of the feeler side of a loom having the present invention associated therewith;

Fig. 2 is an enlarged plan view showing the relation of parts of the feeler mechanism when, on a detecting beat, the impinging and penetrating feelers are in feeling position and a working supply of filling is present in the shuttle;

Fig. 3 is a view similar to that of Fig. 2 60 showing the relation of parts when the filling is substantially exhausted on a detecting beat and the impinging and penetrating feelers are in feeling position; and

Fig. 4 is an enlarged detail view showing 70 the detent mechanism and novel form of means for causing the detent to move the feelers frontwardly beyond the reach of the filling.

The invention is herein shown and will be 75 described in connection with a loom for replenishing the shuttle with filling when that previously in use has reached a degree of substantial exhaustion, but it is to be understood, of course, that the present invention 80 may be advantageously employed in connection with other forms of filling replenishing mechanism, or indeed, with a stopping mechanism, if desired.

It has not been deemed necessary to illustrate herein the details of the replenishing mechanism, because they form no essential 85 part of the present invention.

The loom frame 1 may be of usual construction, having a breast beam 2. Mounted 90 in brackets or supports 3, one at each side of the loom, is the usual transverse or rock shaft 4, from which rises the arm 5 pivotally connected at 6 with a rearwardly extending arm 7, the rear end portion 8 of 95 which is adapted at times to be engaged and moved by an operating member 9 which may be conveniently formed as a part of or connected to the cam follower. Underlying the arm 7 is a finger 10 extending from the lever 11 pivotally mounted at 12 on the loom frame. The opposite end of the lever has connected thereto a slotted cam member 13 through which extends the transmitter 14, the construction being such that should the 100 transmitter 14 be moved frontwardly, it will effect engagement of the arm 7 by the operating member 9 and initiate replenishment of filling or other change in the loom operation.

Extending from the shipper stand is the arm 15 to which is adjustably secured the bracket 16 for the support of the feeler stand 17. In the present instance the feeler stand 17 is secured to the bracket 16 by a bolt 18 which passes through the slot 19 in the feeler stand, whereby the feeler stand may be properly adjusted in position.

In accordance with the present invention, 10 an impinging and a penetrating feeler are employed, both of which are mounted for movement toward and from the front of the loom. In the present instance, the impinging feeler is formed by the rear end portion 15 20 of a feeler carrier or slide 21 mounted on the feeler stand. Extending forwardly from the slide 21 is the feeler stem 22, and a spring 23 interposed between the carrier 21 and the front bearing portion 24 20 of the feeler stand normally impels the slide or carrier rearwardly.

The carrier or slide 21 has a recessed portion 25 in which is mounted a block 26 having secured thereto the penetrating feeler 27, the rear end portion or point 28 of which normally extends beyond or rearward of the impinging feeler 20, the construction being such that should the penetrating feeler be moved forwardly relative to the impinging feeler by engagement with the more dense surface of the filling carrier, the block 26 will be correspondingly moved, and through a train of mechanism to be described, effect replenishment of filling.

Pivottally mounted at 29 on the carrier or slide 21 is the actuator 30, the front end portion of which is provided with a tooth or projection 31. The actuator 30 has a 40 laterally projecting portion 32 through which is threaded the screw 33, capable of adjustment, and held in adjusted position by a lock screw 34. The pivotal support 29 of the actuator is surrounded by a spring 45 35 normally tending to maintain the actuator 30 in its inoperative position, as indicated in Fig. 2.

Extending upwardly from the block 26 is a lug or projection 36 against which the 50 rear end portion of the adjusting screw 33 normally rests. The feeler stand 17 is provided with a stop 37 against which the actuator 30 normally rests to limit the lateral movement of the actuator 30 under the 55 impulse of the spring 35 and permit lateral movement of the actuator 30 in the opposite direction when the penetrating feeler engages the more dense surface of the filling carrier or bobbin on a detecting beat.

60 The block 26 carrying the penetrating feeler is normally under the influence of a light spring 38, Fig. 2, which maintains the projection or lug 36 against the rear end of the adjusting screw 33. The tension of the spring 38, however, is less than the ten-

sion of the spring 35, with the result that when the parts are adjusted relatively in the position indicated in Fig. 2, the projection 36 extending from the block 26 will rest lightly against the adjusting screw 33.

The transmitter 14 may be of usual construction, except that it has mounted thereon the projection 39, which may be in the form of a block secured to the transmitter 14 by a screw 40. The block 39 has a hooked portion 41 which is adapted to be engaged by the tooth 31 of the actuator when the actuator is given a lateral movement by the penetrating feeler upon detection of substantial exhaustion of the filling in the shuttle on a detecting beat, as indicated in Fig. 3. When the tooth 31 is thus engaged with the hook 41 and the feeler carrier on which the impinging and penetrating feelers are mounted, is moved forwardly as the lay beats up, the transmitter 14 will be given a forward movement, as indicated in Fig. 3, and will act through the lever 11 to actuate replenishment of filling.

The lay 42, Fig. 1, is of usual construction, and is provided with a shuttle box 43 in which the shuttle 44 is received. The shuttle 44 has mounted therein the filling carrier 45, of usual construction, and the front wall of the shuttle box and the front wall of the shuttle are each provided with an opening, as indicated in Fig. 1, through which the impinging and penetrating feelers pass on a detecting beat to detect the condition of the filling in the shuttle.

As hereinbefore stated, the recurring contact of the penetrating feeler with the filling on detecting beats is liable to cause injury thereto, and such injury may result even though the penetrating feeler contacts only lightly with the filling. In accordance with the present invention, therefore, means are provided for moving both the impinging and penetrating feelers to a forward inoperative position beyond the reach of the filling on detecting beats, and holding the two feelers in such non-contacting relation with the filling for the periods of inactivity of the feeler. In order that the feelers may act from time to time to detect the condition of the filling in the shuttle, means are further provided for freeing the feelers for movement to the performance of their feeling functions during weaving with the same supply of filling in the shuttle.

Rising from the feeler stand is a bracket 46 on which is pivotally supported a detent or pawl 47 normally under the influence of a spring 48, Fig. 4, tending to move the active end of the detent or pawl 47 into engagement with the feeler stem.

The detent or pawl 47 has a rearward extension 49 to which is pivotally connected at 50 a train of mechanism for controlling

the action of the pawl, and consequently may be referred to as a detent controller. In the present instance the detent controller comprises a rod 51 connected to the pin 50 and itself pivotally attached at 52 to a lever 53 pivotally supported at 54 on a bracket 55 extending downwardly from the shipper stand extension 15. The free end of the lever 53 is connected at 56 to a downwardly extending rod 57 which is pivoted at 58 to a trip lever 59. The trip lever 59 has a hub portion 60 mounted on the projection or dead shaft 61 extending from the loom frame, and a spring 62 normally tends to turn the trip lever 59 in an upward direction, as shown, against the stop 63. From the construction described it will be apparent that should the trip lever 59 have its free end depressed from time to time it will actuate the detent or pawl to free the feelers, as will presently appear, so that the feelers may move to the performance of their feeling functions during periods of activity.

25 The stem 22 of the feeler carrier or slide 21 has a tooth of novel construction, as indicated in Fig. 4, so that should the detent 47 be engaged with the tooth and then be further turned on its pivotal support, it 30 will serve to move the carrier 21 and consequently both the impinging and penetrating feelers to a further frontward position beyond the reach of the filling on detecting beats.

35 The tooth 64, Fig. 4, has a shoulder portion 65 and a locking portion 66, between which is the inclined or cam surface 67, the construction being such that should the impinging and penetrating feelers be moved frontwardly by a working supply of filling on a detecting beat, the detent or pawl 47 will engage the shoulder 65 to retain the feelers in the position to which they have been moved by the filling, and as the detent or pawl 47 is further moved onto the tooth 64 by the combined action of the springs 48 and 62, both feelers will be given an additional frontward movement which will carry them beyond the reach of the filling, and when the detent or pawl has engaged the portion 66 of the tooth 64, both feelers will be retained in this frontward position out of cooperative relation with the filling during periods of inactivity of the feelers.

40 It is desirable that the feelers should be released from time to time to the performance of their feeling function during weaving with the same supply of filling in the shuttle, and to this end the present invention contemplates that the trip lever 59 shall be actuated by a going part of the loom from time to time, then permitted to return to its initial position.

45 In the present instance of the invention,

the train of mechanism for actuating the trip lever 59 is associated with the take-up mechanism, as indicated in Fig. 1. The take-up mechanism comprises the usual train of gearing 68, 69, 70 and 71 which transmits movement to the take-up or sand roll, as usual.

50 Mounted in suitable bearings 72 and 73 connected to the loom frame is a shaft 74 having a gear 75 in operative engagement with one of the gears, such as 69, of the train of take-up mechanism, whereby the shaft 74 is given a slow rotative movement. The shaft 74 carries a disk 76 to which may be secured one or more trip pins 77, so positioned with respect to the end of the trip lever 59 that the latter may be operated from time to time. If desired, the disk 76 may be provided with a series of holes 78 for properly adjusting the trip pin or pins to the recurrent periods of desired release for the penetrating and impinging feelers.

55 The end portion of the trip lever 59 is provided with a shoulder 79 which is engaged by one of the trip pins to release the feelers from their holding relation with the detent or pawl 47, and at the side of the shoulder 79 the trip lever has a surface 80 which serves to hold the detent or pawl 47 in its position for engagement with the shoulder 65 of the tooth 64 when the two feelers are moved frontwardly by a working supply of filling in the shuttle on a detecting beat, and when the end of the trip lever 59 has been freed by the actuating trip pin, 60 the springs 48 and 62 will act upon the detent or pawl 47 and cause it to travel over the cam or inclined portion 67 of the tooth 64 thereby withdrawing the two feelers further frontwardly beyond the reach of 65 the filling, and when the end of the detent or pawl rests in the portion 66 of the tooth 64, Fig. 4, both feelers will be held in their frontward inoperative position until the trip lever is again actuated. Thus the impinging and penetrating feelers have periods of activity and inactivity during weaving with the same supply of filling in the shuttle, and when in their inactive position both feelers will be held frontwardly 70 beyond the reach of the filling on detecting beats.

60 Assuming that the impinging and penetrating feelers are in their rearward feeling position, as indicated in Fig. 2, and a working supply of filling is present in the shuttle, the latter will move the carrier or slide 21 frontwardly as the lay moves up to front position on a detecting beat, and the shoulder 65 of the tooth 64 will be engaged by the detent or pawl 47. When the trip lever 59 is entirely released from engagement with the trip pin, the pawl will act on the cam portion of the tooth to move both feelers frontwardly beyond the 75 80 85 90 95 100 105 110 115 120 125 130

reach of the filling and will hold them in such position during the period of inactivity of the feelers or until both feelers are again released by the controlling mechanism.

5 Should the filling have been depleted to a degree approaching substantial exhaustion on a detecting beat when the feelers are in their feeling position, the feeler carrier 21 will not be moved frontwardly sufficiently far to permit the detent or pawl 47 to engage the tooth 64, and both feelers will remain in operative feeling position and call for a change of filling when that in the shuttle has become substantially exhausted. In this action, the penetrating feeler will act to move the actuator 30 in a lateral direction to cause the tooth 31 of the actuator to engage the hook 41 associated with the transmitter and will act therethrough to actuate replenishment of the filling when the filling is substantially exhausted.

What is claimed is:

1. In a feeler mechanism for looms, the combination of an impinging and penetrating feeler, a detent for holding both feelers in a frontward inoperative position, and means for freeing the feelers at intervals, comprising a shaft driven from the take-up mechanism, a disk rotating with the shaft and having a trip pin extending therefrom, a trip lever extending in a plane parallel to the face of the disk and adapted to be actuated by the trip pin, and connections between the trip lever and detent for freeing the feelers from the detent when the trip lever is actuated by the trip pin.

2. In a feeler mechanism for looms, the combination of an impinging feeler, a penetrating feeler normally extending beyond the end of the impinging feeler, a detent and cooperating means including a tooth connected to the impinging feeler and having a holding and cam portion for withdrawing both feelers frontwardly into a position beyond the reach of the filling on detecting beats and holding them in such position during their periods of inactivity, and means for freeing the feelers at intervals that they may move to the performance of their feeling functions during weaving with the same supply of filling in the shuttle.

3. In a feeler mechanism for looms, the combination of two feelers, one an impinging feeler having a frontwardly extending stem provided with a shoulder and a cam portion and the other a penetrating feeler normally extending beyond the end of the impinging feeler, a carrier on which the feelers are supported, a detent for engaging the shoulder of the tooth when the feelers are moved frontwardly by a working supply of filling, means for forcing the

detent over the cam of the tooth to withdraw the feelers to a position beyond the reach of the filling on detecting beats, and means actuated by a going part of the loom for freeing both feelers to the performance of their feeling functions at intervals during weaving with the same supply of filling in the shuttle.

4. In a feeler mechanism for looms, the combination of an impinging and a penetrating feeler, a transmitter adapted to be actuated when the penetrating feeler meets the dense surface of the filling carrier in the shuttle on a detecting beat, a stem extending frontwardly from the impinging feeler and having a tooth provided with an upper and a lower holding shoulder and a cam or incline between them, a detent to engage the upper shoulder when the feelers are moved frontwardly by a working supply of filling, means for forcing the detent over the cam portion of the tooth into engagement with the lower shoulder to withdraw the feelers frontwardly, and means for freeing the feelers from the detent at intervals.

5. In a feeler mechanism for looms, the combination of an impinging feeler having a frontwardly extending stem provided with a tooth having a cam surface, a penetrating, feeler slide mounted on the impinging feeler and carrying a penetrating feeler normally urged rearwardly of the impinging feeler, a detent pivotally supported in fixed position for engagement with the cam tooth on the feeler stem, a rod connected to the detent for turning the detent in either direction, a lever connected to and for forcibly operating the detent, a second rod connected to the lever, and means operating thru said rods and levers for forcing the detent over the cam surface of the tooth to withdraw both feelers frontwardly.

6. In a feeler mechanism for looms, the combination of a feeler mounted for movement towards and from the front of the loom, a frontwardly extended part connected thereto and having a tooth provided with a cam portion, a detent for engaging the tooth when the feeler is moved frontwardly by a working supply of filling on a detecting beat, means acting upon or through the detent to cause the latter to move along the cam of the tooth to withdraw the feeler to a frontward position beyond the reach of the filling on detecting beats, and a trip for freeing the detent from the tooth at intervals that the feeler may have periods of activity and inactivity during weaving with the same supply of filling in the shuttle.

In testimony whereof, I have signed my name to this specification.

EDWARD A. CUNNIFF.
